RETURN BEND FITTING FOR OIL STILLS

Charles E. Ard, Birmingham, Ala., assignor to
Fred C. Fantz, Webster Groves, Mo.Application January 25, 1933, Serial No. 653,395
Renewed December 7, 1934

2 Claims. (Cl. 285—20)

My invention relates to that class of bends which provide for demountable tubes mounted in a solid housing.

My invention has for its principal object to provide a device in which the still tubes are demountably mounted in the housing, but which can be light in weight, which will be easy to machine, and which will facilitate the removal of the sectional rings or bushings mounted intermediate the tubes and the annular portions which encircle the ends of the tubes, which will eliminate the separate toggles and set screws and yet make it possible to gain quick and convenient access to the interior of the tubes for the purpose of removing accumulations of coke, which is essential for the safe operation of cracking stills.

My means of accomplishing the foregoing objects may be more readily understood by having reference to the accompanying drawings which are hereunto annexed and made a part hereof, in which

Fig. 1 is a side elevation of the fitting in its assembled position, part of it being broken away showing some of the parts in section;

Fig. 2 is a top or plan view of the device as shown in Fig. 1, the housing section and tube on the left side being omitted;

Figs. 3, 4 and 5 are detail views of one of the housing sections;

Fig. 6 is a side elevation of the bottom plate;

Fig. 7 is a section on the line 7—7 in Fig. 2;

Fig. 8 is a top plan view of a modified form of plate;

Fig. 9 is a side elevation of the same;

Fig. 10 is a section on the line 10—10 in Fig. 8;

Fig. 11 shows the modified form of housing to be employed in connection with the plate shown in Fig. 8; and

Fig. 12 is a top plan view of the same.

Similar reference numerals refer to similar parts throughout the entire description.

As shown in the drawings I have provided a conventional return bend which is suitably connected to a pair of adjacent still tubes 2 and 3, a fragmentary portion of the tubes only being shown as it is apparent they form no part of my invention. The return bend 1 is mounted in a compound housing which comprises two inverted U shaped members 4 and 5 which have side walls 6 and 7 which terminate in inwardly extending arcuate lugs 8 and 9. The side walls of the U are joined at their top by cross members 10 which are provided with central hubs 11 in which is mounted set screws 12, the inner ends

of which are adapted to engage abutments 13 formed on the external surface of the return bend 1.

The lower part of the housing comprises a plate 14 which consists of two annular portions 15 adapted to encircle the ends of the still tubes 2 and 3 on which are provided inwardly extending shoulders 16 which engage the upset shoulders formed on the still tubes through the medium of sectional metal rings 18 which are inserted intermediate the shoulders on the annular portions and the external surface of the still tubes.

The annular members 15 are provided with bayonet slots 17 which are adapted to receive 18 the inwardly extending lugs 8 and 9 on the side walls 6 and 7.

The device is assembled as follows:

The ends of the tubes 2 and 3 are passed through the plate 14 and the sectional rings 18 are inserted in position. The plate 14 is then drawn up until the shoulders 16 engage the shoulders on the still tubes. The lugs 8 and 9 are then inserted in the slot 17 and the yoke is given a partial turn until the lugs 8 and 9 are brought in contact with the stop 19 at the end of the bayonet slots 17 when by tightening the set screws 12 it is apparent that the face of the return bend will be forced tightly against the ends of the tubes, forming a leak-proof joint.

In some cases it may be found desirable to construct the device with the modified form of construction shown in Figs. 8 to 12 in which the lugs 8 and 9 are provided with an inclined surface as at 20. The upper wall of the bayonet slots 17 being correspondingly inclined with the result that any tendency on the part of the side walls 6 and 7 to spread when the set screw is tightened is entirely overcome. It may, in some cases, be desirable to provide means to prevent the bottom plate from dropping down on the tubes when the U or return bend is removed for this purpose. I have shown in Fig. 1 a set screw mounted in one of the annular portions 15 of the bottom plate. Although I show a specific type of fastening device for this purpose, obviously any desired means for holding the bottom plate in place may be employed.

It will be apparent to persons skilled in the art that a fitting of this construction is peculiarly adaptable for low pressure service, as it is inexpensive to manufacture and is comparatively light, and yet will furnish a satisfactory fitting for such service.

Having described my invention, what I regard

as new and desire to secure by Letters Patent is:

1. In a refinery apparatus, a conventional return bend adapted to connect a pair of still tubes to provide a passageway therethrough, the ends 5 of said tubes being upset to form external shoulders, a housing therefor, comprising a pair of inverted U shaped members, the side walls of which terminate in inwardly extending lugs, the upper surface of which inclines upwardly and inwardly 10 set screws which abut said return bend mounted in the upper part of said inverted U, a plate having annular portions adapted to encircle the ends of said tubes, internal shoulders formed in said annular portions, sectional metal bushings 15 adapted to be mounted intermediate said annular portions and said tubes to abut said shoulders, there being bayonet slots in said annular portions adapted to receive said inwardly extending lugs, the upper walls of said slots being fitted to and coinciding with the said inwardly extending lugs, 20 means to prevent the rotation of said U's in said slots beyond a predetermined point.

2. In a refinery apparatus, a conventional return bend adapted to connect a pair of still tubes to provide a passage way therethrough, the ends of said tubes being upset to form external shoulders, a housing therefor, comprising a pair of inverted U shaped members, the side walls of which terminate in inwardly extending lugs, set screws which abut said return bend mounted in the upper part of said inverted U, a plate having annular portions adapted to encircle the 10 ends of said tubes, internal shoulders formed in said annular portions, sectional metal bushings adapted to be mounted intermediate said annular portions and said tubes to abut said shoulders, there being bayonet slots in said annular portions 15 adapted to receive said inwardly extending lugs, means to prevent the rotation of said U's in said slots beyond a predetermined point, and means on said lugs to prevent the walls of the U spreading when the set screws are tightened. 20

CHARLES E. ARD.
